UNITED STATES PATENT OFFICE

2,420,511

APPARATUS FOR FORMING AND ASSEMBLING INNER SPRING CONSTRUCTIONS

Edward E. Woller, Kenosha, Wis., assignor to Simmons Company, New York, N. Y., a corporation of Delaware

Application September 7, 1942, Serial No. 457,584

14 Claims. (Cl. 140—3)

1

This invention relates to an improved apparatus for making and assembling inner spring constructions such as are employed in inner spring mattresses and like cushion structures.

Machines have heretofore been devised for assembling coil springs and uniting rows thereof by means of wire helices fed endwise and rotated and guided so as to be threaded around juxtaposed coil portions of the springs. In the machines heretofore devised the coil springs were preformed and the coil portions thereof which are embraced by the tying helix may be straightened out somewhat to facilitate threading of the helix therearound, the straightened coil portions being thereafter permitted to return to approximately normal position. The return of the straightened coil portions to approximately normal condition results in a desirable binding effect which prevents the production of rattling noises in the spring construction incident to relative moving of the spring coils and helices.

Spring constructions have also been made wherein the springs have their end coils preformed with specially shaped offsets which more or less interfit when the springs are arranged in rows, the offsets sometimes being disposed substantially in contact with each other and sometimes in relatively offset relation, the usual wire helices being employed to unit such preformed spring coil portions.

The present invention has for one of its objects the provision of means for holding springs in predetermined relationship while a wire helix is threaded around predetermined portions of the springs to tie them together and to incorporate in such holding mechanism, means for forming offsets of the character referred to, thereby to eliminate an extra handling of the springs which would be required if they were to be placed in mechanism for forming the offsets before being placed in the apparatus for tying them together by means of the wire helices.

Other objects of the invention are to provide combined mechanism of the character indicated which will be operative at fairly high speed so as to provide an adequate rate of inner spring unit production; to provide apparatus of the character indicated which will be automatic in operation and will not require manual handling or operations; and in general it is the object of the invention to provide improved apparatus of the character indicated.

Other objects and advantages of the invention will be understood by reference to the following specification and accompanying drawings (four

2

sheets) wherein there is disclosed apparatus for the production of two forms of coil offsets together with certain elements of mechanism for holding the springs with their offsets in juxtaposed position and means for guiding a helical wire around the coil offsets.

In the drawings:

Fig. 1 is a fragmentary plan.

Fig. 2 is a section on the line 2—2 of Fig. 1.

Fig. 3 is a section on the line 3—3 of Fig. 1.

Fig. 4 is a section on the line 4—4 of Fig. 3.

Fig. 5 is a plan of one element of mechanism appearing in the other figures and illustrating certain details thereof.

Fig. 6 is a fragmentary plan view corresponding to Figure 1 but showing a modified arrangement.

Figs. 7 and 8 are sections respectively on the lines 7—7 and 8—8 of Figure 6.

Fig. 9 is an end elevation of the spring coil forming and gripping end of one of a pair of co-operating jaws, the location of this view being substantially as indicated by the line 9—9 of Figure 7.

Fig. 10 is a fragmentary plan of one element of mechanism appearing in the construction shown in Figure 6 to 8 and in Figure 11.

Fig. 11 is a fragmentary plan section approximately on the plane indicated by the line 11—11 of Fig. 7.

The mechanism herein disclosed is adapted to be employed in apparatus such as shown in Patent No. 1,905,459 to Gail and in my Patent No. 2,388,106 to me. In the mechanism herein disclosed certain jaw parts are movable toward and from each other and toward and from a guide track substantially as are counter-parts of the mechanism shown in said Gail patent and in my said patent. Reference is therefore made to said patents for a complete disclosure of the mechanism for actuating the parts of the mechanism herein disclosed.

Referring first to Figures 1 to 5 inclusive, there is there shown mechanism including a pair of jaws 12 and 13, the same being suitably mounted for sliding movement toward and from each other on a bed plate 14 mounted on a suitable supporting frame structure 15. The jaw 12 is adapted to be reciprocated in an endwise direction by means of a rock arm 16 pivotally mounted intermediate its ends as indicated at 17 to a bracket carried by the frame 15. The jaw 13 is similarly actuated by means of an arm 18 pivotally mounted intermediate its ends as shown at 19 on a suitable bracket carried by the frame 15.

The arms 16 and 18 have their lower ends (not shown) suitably connected to mechanism for rocking the arms and the upper ends of the arms are equipped with anti-friction rollers disposed in suitable recesses or openings in the jaws 12 and 13 for transmitting rocking movement of the upper ends of said arms into sliding movement of the respective jaws. The arms 16 and 18 are so actuated that the jaws 12 and 13 simultaneously move toward each other and later away from each other.

The relatively adjacent ends of the jaws 12 and 13 also cooperate with a guide track 20 which is suitably mounted in the bed plate 14 or other supporting parts, preferably as shown in my said co-pending application. The guide track 20 consists of a series of sections such as shown in Figure 1, the sections being arranged end to end to form a continuous, elongated track extending for the full length of rows of coil springs which are to be united by wire helices.

The track section 20 associated with each pair of jaws is provided adjacent the opposite sides of the jaws with upstanding flange elements 21, 22, 23, and 24 which cooperate with the track element 20 to form a channel structure of substantially the same depth as the outside diameter of the helix employed, one of which is illustrated at 25.

Coil springs indicated 26 and 27 respectively each represent one spring of a row of such springs which are to be joined by a helix such as 25. The coil springs, when delivered to the apparatus, are of normal, approximately circular formation.

The jaw 13 has its operative end shaped to substantially correspond to the interior of an offset to be formed in the terminal coil of the spring 27. The track element 20 is provided with a recess 28 of a depth substantially corresponding to the thickness or diameter of the wire in the coil spring 27. Said recess is shaped to cooperate with the operative end portion 13a of the jaw 13 to form an offset having an initially straightened portion 29 and end portions 30-30 making the elongated straightened portion 29 in the coil body proper. (see Figure 4).

As best shown in Figure 4, the flange elements 22 and 24 of the guide track structure have their ends so shaped as to constitute continuations of the shoulder or recess 28 in the track bar 20 for also cooperating with the adjacent end portion of the jaw 13 to form said offset.

The jaw 13 is also preferably provided with ear portions 31-31 on its opposite sides for engaging the spring coil 27 to bend the same around the adjacent rounded corner portions of the guide track flanges 22 and 24. Said ear portions 31 are preferably recessed as indicated at 32 to receive the adjacent portions of the coil 27 so as to prevent lateral displacement thereof incident to the forming pressure developed in the operation of the jaw.

The jaw 12 similarly has its operative end provided with a seat 33 having rounded receding end portions 34-34 for bending a part of the terminal coil of the spring 26 to substantially straight form indicated at 35 but without forming any permanent or sharp bends or end shoulders or legs such as the shoulders 30 formed in the spring coil 27. The rounded end portions 34 of the seat in the jaw 12 cooperate with suitably chamfered corners 35 of the helix guide track flange elements 21 and 23. The seat portion 33 of the jaw 12 cooperates also with a cor-

respondingly formed shoulder portion 36 of the jaw 13 (see Figure 3) to grip and hold the straightened coil portion 39 in its straightened position substantially overlying the straightened offset portion 29 of the coil 27. The jaw 12 also is provided with a lip portion 37 which, as shown in Figure 3, extends over the uppermost coil portion 39 so that the jaw 12 cooperates with the jaw 13 and with the track 20 to completely enclose said coil portions 29 and 39.

The track 20 is provided with helically disposed grooves 38 corresponding to the pitch and lead of the helix 25 and the adjacent or cooperating ends of the jaws 12 and 13 are also provided with grooves 12b and 13b respectively which constitute, in effect, continuations of the grooves 38. The grooves in the ends of the jaws and the grooves in the track 20 serve to permit the helix 25 to be rotated and fed endwise between the jaws while said jaws are cooperating to hold the springs 26 and 27 with the offset and flattened portions formed therein substantially as shown in Figure 4. When the helix is so guided and fed endwise, it will of course be wound around the juxtaposed spring coil portions 29 and 39.

When the jaws 12 and 13 are opened up or moved from each other and from the track 20, the inherent resiliency of the spring wire employed in the coils 26 and 27 will cause the flattened and offset coil portions 39 and 29 to resume a more or less arched formation as illustrated at the righthand end of Figure 1. Such return to arcuate form from the straightened form produced by the jaws is desirable in that it tends to create pressure points between the spring coil portions and the helix 25 which prevent relative shifting and incidental rattling noises in the spring construction unit. The extent to which the flattened portions will return to arcuate form depends of course somewhat upon the resiliency of the wire employed in making the springs. Some control of the final form of the offsets is possible by appropriately shaping the cooperating ends of the jaws within limits dictated by the requirements of effecting sufficient straightening of the coil portions to insure free travel of the helix around the same.

In the arrangement shown in Figures 6 to 11 inclusive the terminal coils of springs designated 40 and 41 respectively have relatively short offsets 42 and 43 respectively formed therein and held in longitudinal, substantially co-axially alignment while a wire helix 44 is threaded around the same. The wire helix 44 is guided by a suitably grooved track section 45 which substantially corresponds to the track section 20 shown in Figures 1 to 5 inclusive except that in the track section 45 oppositely facing recessed seats 46 and 47 are formed for cooperating with portions of jaws 48 and 49 respectively to form the said offsets 42 and 43.

The jaws 48 and 49 are mounted for sliding movement toward and from each other and toward and from the guide track 45, said jaws being so mounted on a bed plate 50 which corresponds to the bed plate 14 in the structure shown in Figures 1 to 5 inclusive. The track 45 is also suitably mounted on said bed plate in fixed position thereon.

The track 45 has associated therewith upwardly extending flange pieces 51, 52, 53, and 54, said flange pieces being suitably rigidly secured to the sections and held therewith in fixed relation to the bed plate 50 on which the jaws are slidably mounted.

The jaws 48 and 49 are substantially aligned and they each have projections designed to cooperate with the seats 47 and 46 respectively of the track 45 to form the relative staggered offsets 42 and 43 in the coils 41 and 40 respectively.

The projection 56 of the jaw 49 has an end portion 57 formed to cooperate with the shoulder or seat 46 in the track 45 to form the offset 42. Said projection 56 is also so shaped as to cooperate with an ear or lug 58 formed on the guide track flange 52 and with a suitably shaped recessed portion 59 of the guide track flange element 54 to form the end portions or legs 60 and 61 of the offset 46 in the coil 41.

The projection 55 of the jaw 48 is similarly formed to cooperate with the recessed seat or shoulder 47 in the track 45 and with an ear portion 62 formed on the flange element 53 and a suitably recessed seat 63 formed in the adjacent end portion of the flange element 51. The projecting portions 55 and 56 each have upper portions 64 and 65 respectively which extend over the respectively engaged spring coil portions to move the same downwardly to the respective seats 47 and 46 in the track 45 and to hold the same in cooperative relation to said seats while the respective jaw projections enter said recessed seats to form the offsets in the spring coils.

When the springs are initially delivered to the jaws, they may not immediately rest on the track 45 but the inclined cam-like surfaces 66 and 67 of said projecting portions 64 and 65 respectively will serve to cam said coil portions downwardly into operative relation to the offset forming portions such as 57 of the jaws and the track seats 46 and 47.

Each of the jaws 48 and 49 have mounted therein a spring-coil holding pin such as 68. Said pin 68 extends length-wise of the respective jaws and about centrally of the respective offset forming projections 55 and 56 therein as best shown in Figure 6.

Each spring-coil holding pin 68 is longitudinally slidably mounted in a suitable bore 69 provided in the jaw, a coil spring 70 being provided around a portion of the pin for urging said pin to move outwardly of the respective ends of the jaw projections 55 and 56. The springs 70 are fairly stout springs and under compression between the enlarged outer end portion 71 of each pin and the bottom shoulder 72 of the recess 69. Movement of the respective pins 68 under the influence of the spring 70 may conveniently be limited by providing the inner end portion 73 of each pin with a cross pin 74 extending diametrically through the pin 73. Limited movement of the pin 68 is permitted by providing an opening 75 in the jaw for the pin 74, said opening 75 being of such size as to permit the desired extent of movement of the pin 68 relative to the jaw.

The outer end of the pin 68 has a radially upwardly extending lug or key-like portion 75 formed integral therewith and slidably mounted in a guideway 76 shaped to slidably receive said key-like portion 75.

After the jaws 48 and 49 have been moved to their limited movement toward the track 45 and have completed the formation of the offsets 42 and 43 in the spring coils, the jaws are retracted slightly. When the jaws are retracted to the limited extent indicated, the spring-pressed pins 68 are forced outwardly by the respective springs 70 so as to cause the key-like heads 75 of the pins

to remain in the position shown in Figure 11 relative to the track 45 and the coil offsets 42 and 43 formed therein, thereby to hold said coil offsets in said position relative to the track while the helix 44 is threaded around said coil offset portions 42 and 43. In Figure 11 the jaws are shown in their innermost position and before the same are retracted. In Figure 6 the jaws are shown retracted to such an extent that the offset-forming ends such as 57 thereof are disposed approximately in registration with the inner walls of the flanges of the guide track 45. Hence said offset-forming ends of the jaws do not interfere with the free passage of the helix and the winding thereof around the spring coil offsets. The heads 75 of the holding pins are, however, suitably grooved as indicated at 77 to form, in effect, continuations of the helical guide grooves of the track 45 to thereby permit the winding of the helix around the offset portions notwithstanding the holding thereof in place on the track by said holding pins.

After the helix has been threaded for the entire length of the spring rows to be assembled, the jaws 48 and 49 are further retracted so as to withdraw the holding pins 68 from engagement with the coil offsets. The helically connected coil springs may then be elevated and moved laterally over the jaws preparatory to the next coil offset-forming and helical-tying operation. In Figure 6, there is illustrated an arm 78 having a double hooked end portion 79 which is adapted to be moved upwardly to raise the connected coils above the top of the jaws and then moved laterally to feed the connected spring rows laterally substantially as shown in the said Gail patent and in my said co-pending application. The jaw 49 is suitably recessed as indicated at 80 and the flange element 54 is suitably recessed as shown at 81 to permit the required endwise movement of the hooked member 78 into operative position relative to the coil. Similarly the jaw 48 is grooved as indicated at 82 to permit the operation of a spring construction lifting and feeding device such as 78, also in keeping with said patent and co-pending application.

When the springs 40 and 41 (Figure 6) are displaced from the track 45 and released from the respective jaw ends, the inherent resiliency of the wire of which the springs are formed causes the offset portions 42 and 43 to at least partially return to their initially curved condition, the result being that said offsets will appear approximately as shown at the righthand end of Figure 6. As there shown, the offsets 42 and 43 are more or less curved and approximate a condition in which they will have engagement with opposed turns of the helix 44 whereby undesirable shifting of the offset portions 42 and 43 within the helix will be resisted. It is not, however, important that the offsets 42 and 43 resume sufficient curvature to actually engage opposed portions of the helix since it is quite feasible to produce the offsets of such length that the end legs 85 and 86 thereof will have firm engagement with certain turns of the helix 44 substantially as indicated at 87. The helix may in effect be slightly compressed between the legs 85 and 86 of each of said offsets to thereby insure the maintenance of contact between the helix and offsets to prevent undesirable relative movement between said parts. It may be noted that as shown in Figure 6 the offsets 42 and 43 will remain in substantially straight condition when held in the track seats 46 and 47 by the holding elements 75, this being

due to the presence of the respective jaw projections between the legs 85 and 86 which serve to hold the latter in substantially fixed position between the respectively adjacent ends of the side flange elements 52 and 54 or 51 and 53.

For the same purpose the track 20 is recessed as shown at 83 and the jaw 12 recessed as shown at 84 in the construction shown in Figures 1 to 5 inclusive.

It will be understood that although there has been illustrated and described in this application only one set of jaws for acting on juxtaposed coil portions of springs in adjacent rows, that in a full sized spring assembling machine, such as shown in the Gail patent and in my said co-pending application, a plurality of sets of jaws such as shown and described are contemplated, there being one set of jaws for each spring in the rows of springs to be united. Furthermore, in respect of the arrangement shown in Figures 1 to 5 of this application, the cam operating means for actuating the jaws of the said patent and co-pending application may be employed or that other arrangements may be employed if desired or found necessary to supply the force required to form the offsets in the springs. In respect of the actuation of the jaws in the form of construction represented in Figures 6 to 11 inclusive, the cam operating means shown in said patent and co-pending application typify one form of operating mechanism, although it will be apparent that some slight modification of the cam will be required to produce the two-step retracting movement of the jaws, the operating cam mechanism may in general be of the same character as shown in said patent and co-pending application. The required cam modification involves merely proper designing of the cam to produce the required movement and, being an ordinary mechanical expedient, is not herein illustrated.

Apparatus embodying the jaw constructions herein described will have conventional coil springs delivered to it, will operate on said springs to form the offsets desired, effect tying of the springs together by means of helicals and will advance the tied-together spring rows to permit the delivery of another row of springs into juxtaposition with the trailing end of the previously united spring rows. The mechanism herein described thus serves to completely eliminate the independent handling and forming of offsets in the spring coils which are initially formed in substantially spiral or circular form by any suitable spring wire coiling mechanism.

Changes in the described construction may be made without departing from the spirit of the invention, the scope of which should be determined by reference to the following claims, the same being construed as broadly as possible consistent with the state of the art.

I claim:

1. In apparatus of the class described, a normally stationary track member for guiding a rotating helix in an endwise direction, a pair of jaws respectively disposed on opposite sides of said track member and movable toward and from the same, said track member being provided with a recessed seat, and one of said jaws being provided with an end formation adapted to force a portion of a spring coil into said seat to form an offset in the spring coil, said jaws and track cooperating to hold coil portions of juxtaposed springs in predetermined position relative to said track so as to cause a rotating helical wire mov-

ing endwise along said track to be wound around said coil portions to thereby tie said springs together.

2. In apparatus of the class described, a normally stationary track member for guiding a rotating helix in an endwise direction, a pair of jaws respectively disposed on opposite sides of said track member and movable toward and from the same, said track member being provided with a recessed seat and one of said jaws being provided with an end formation adapted to force a portion of a spring coil into said seat to form an offset in the spring coil, flanges extending upwardly from the opposite sides of said track and on opposite sides of said offset forming jaw for cooperating with said track to guide said helix, said flanges having end portions constituting lateral extensions of the end walls of the recess in said track for also cooperating with said jaw end formation to form laterally extending end legs in said offset, said jaws and track cooperating to hold coil portions of juxtaposed springs in predetermined position relative to said track so as to cause a rotating helical wire moving endwise along said track to be wound around said coil portions to thereby tie said springs together.

3. Apparatus according to claim 2 wherein said one jaw is provided with ears for cooperating with the ends of said flanges to effect bending of said laterally extending offset leg portions relative to the normal curvature of the coil portion in which the offset is formed.

4. In apparatus of the class described, a normally stationary helically grooved track member for guiding a rotating helix in an endwise direction, a pair of jaws respectively disposed on opposite sides of said track member and movable toward and from the same, said track member being provided with a recessed seat and one of said jaws being provided with an end formation adapted to force a portion of a spring coil into said seat to form an offset in the spring coil, said jaws having their adjacent ends provided with helically disposed grooves constituting, in effect, continuations of the grooves in said track when the jaws are in closed position relative to the track for permitting free movement of the helix between the jaws and track, said jaws and track cooperating to hold coil portions of juxtaposed springs in predetermined position relative to said track so as to cause a rotating helical wire moving endwise along said track to be wound around said coil portions to thereby tie said springs together.

5. In apparatus of the class described, a normally stationary track member for guiding a rotating helix in an endwise direction, a pair of jaws respectively disposed on opposite sides of said track member and movable toward and from the same, said track member being provided with a recessed seat, and one of said jaws being provided with an end formation adapted to force a portion of a spring coil into said seat to form an offset in the spring coil, said jaws having cooperating end portions operative to grip and hold a portion of another spring coil in predetermined condition and juxtaposition relative to said offset, whereby said jaws and track cooperate to hold coil portions of juxtaposed springs in predetermined position relative to said track so as to cause a rotating helical wire moving endwise along said track to be wound around said coil portions to thereby tie said springs together.

6. Apparatus according to claim 5 wherein said pair of jaws cooperate to distort the second coil

portion from normal curved condition to relatively straightened condition approximately registering with the offset formed in the first mentioned coil portion to thereby facilitate encircling of said coil portions by said helical wire as an incident to its endwise movement while rotating.

7. In apparatus of the class described, a normally stationary track member for guiding a rotating helix in an endwise direction, a pair of jaws respectively disposed on opposite sides of said track member and movable toward and from the same, said track member being provided with a pair of longitudinally spaced, oppositely facing recessed seats respectively opening to the opposite sides of the track, and said jaws being respectively provided with projections respectively adapted to force portions of spring coils into said seats to form offsets in such spring coil portions, means for temporarily holding said offset coil portions in said seats so as to permit sufficient retraction of said jaws to clear said offset portions for encirclement thereof by a rotating helix moving endwise along said track member.

8. Apparatus according to claim 7 wherein said offset holding means comprise members carried by said jaws and mounted therein for limited movement inwardly and outwardly of the ends of said jaw projections.

9. In apparatus of the class described, a normally stationary track member for guiding a rotating helix in an endwise direction, a jaw mounted for movement toward and from one side of said track, said track member being provided with a recessed seat opening to said side thereof, and said jaw being provided with a projection adapted to force a portion of a spring coil into said seat to form an offset in said spring coil, an offset holding element mounted in said jaw for movement inwardly and outwardly of said projection, means for urging said holding element toward said track member to hold said offset in fixed position in said seat while said jaw moves away from said track, thereby to clear said offset for encirclement by a rotating helical wire moving endwise along said track.

10. Apparatus according to claim 9 wherein said track member is provided with helically disposed grooves for guiding said helical wire and wherein said offset holding element is provided with a groove constituting, in effect, a continuation of one of said track grooves for guiding the helical wire around said coil offset.

11. Apparatus according to claim 9 wherein there is provided a pair of said jaws respectively disposed on opposite sides of said track and movable toward and from the same, and wherein the jaw projections are disposed in relatively staggered relation and said track is provided with a pair of seats for respectively cooperating with 60 said jaw projections.

12. In a machine for uniting coil springs, cooperating, relatively movable members adapted to hold between them and thereby position a spring coil portion for the application of a uniting means, one of said members being provided with a recessed seat and the other with a projection which is operative as an incident to relative movement of the members into spring coil holding position, to force a portion of said coil into conformity 5 with said recessed seat, thereby to form a permanent offset in said spring coil for facilitating the application of said spring uniting means.
13. In a machine for uniting coil springs, cooperating, relatively movable members adapted to hold between them and thereby position a spring coil portion for the application of a uniting means, said members being provided with cooperating shoulder portions which extend transversely of the spring coil and are operative as an 10 incident to relative movement of the members into spring coil holding position, to bend a portion of the coil to a laterally extending offset position relative to the remainder of the spring coil, thereby to form an offset for facilitating the application of said spring uniting means.
14. In a machine for uniting coil springs, cooperating, relatively movable members adapted to hold between them and thereby position a spring coil portion for the application of a uniting means, said members being provided with spaced 15 pairs of cooperating shoulder portions which extend transversely of the spring coil and are operative as an incident to relative movement of the members into spring coil holding position, to bend spaced portions of the coil to laterally outwardly extending offset positions relative to the remainder of the spring coil, the coil portion extending between the outer ends of said offsets being thereby also offset from said spring coil 20 for receiving the spring uniting means.
15. In a machine for uniting coil springs, cooperating, relatively movable members adapted to hold between them and thereby position a spring coil portion for the application of a uniting means, said members being provided with spaced pairs of cooperating shoulder portions which extend transversely of the spring coil and are operative as an incident to relative movement of the members into spring coil holding position, to bend spaced portions of the coil to laterally outwardly extending offset positions relative to the remainder of the spring coil, the coil portion extending between the outer ends of said offsets being thereby also offset from said spring coil 25 for receiving the spring uniting means.

EDWARD E. WOLLER.
